(57) **CLAIM**

I claim the ornamental design for a baseball accessories holder, as shown and described.

DESCRIPTION

FIG. 1 is a perspective view of a baseball accessories holder, showing my new design;

FIG. 2 is an enlarged front elevational view thereof, illustrated in a flat configuration;

FIG. 3 is a rear elevational view of FIG. 2;

FIG. 4 is a left-side elevational view of FIG. 2;

FIG. 5 is a right-side elevational view of FIG. 2;

FIG. 6 is a top plan view of FIG. 2; and,

FIG. 7 is a bottom plan view of FIG. 2.

The broken lines showing a baseball bat, helmet and gloves in FIG. 1 are for the purposes of illustrating environment and form no part of the claimed design.

The remaining broken lines represent stitching, and are part of the claimed design.
